ATTYS.

UNITED STATES PATENT OFFICE.

ROBERT JOSEPH NOTT, OF VICTORIA, BRITISH COLUMBIA, CANADA.

BOILER.

1,376,158.

Specification of Letters Patent. Patented Apr. 26, 1921.

Application filed June 7, 1919. Serial No. 302,498.

To all whom it may concern:

Be it known that I, ROBERT JOSEPH NOTT, a subject of the King of Great Britain, and a resident of the city of Victoria, in the 5 Province of British Columbia, Canada, have invented certain new and useful Improvements in Boilers, of which the following is a specification.

My invention relates to improvements in 10 boilers, with more particular reference to boilers used for heating purposes, and the object of my invention is to devise a boiler provided throughout with double return flues whereby the heating surface is greatly 15 increased over that obtained in boilers having single flues, thus enabling quicker action and increased economy of fuel to be obtained.

I attain this object by the construction 20 illustrated in the accompanying drawings in which—

Figure 1 is a side elevation of the boiler, in part section.

Fig. 2 is a reduced front view of the flue 25 headers.

Fig. 3 is a fragmentary sectional view of a pair of headers.

Similar figures of reference indicate similar parts throughout the several views.

30 1 and 2 indicate the front and rear headers superposed one above the other between which extend a plurality of large tubes 3 arranged in parallel rows and the interiors of which tubes are in communication with 35 the interiors of the headers. The upper rows of tubes are longer than the lower rows and their rear headers rest on the top edge of the rear wall 4 of the boiler setting and extend into the outlet flue 6, as shown. The 40 rear header of the lowest row of lower tubes rests on the bridge 7, while the front headers of all the rows rest on the front wall 8 and in front of them is arranged a smokebox 9.

45 10 indicates small tubes extending through the larger tubes 3 and the headers 1 and 2, the interiors of which tubes communicate at their front ends with the smokebox 9 and at their rear ends, as to the upper rows extending 50 through the long tubes 3, with the flue 6, and as to the lower rows extending through the short tubes 3, with the main space 12 inclosed within the walls of the setting the

rear wall of which is spaced away from the rear headers of the short tubes to allow free 55 passage of the hot gases through the same.

The interiors of the headers, which are supplied with water from a suitable source by any suitable means, are connected together by push nipples 13 so that the water 60 may circulate freely through them, the water outlets and returns being indicated by the numerals 14 and 15 respectively.

16 indicates the furnace arranged directly underneath the lower rows of tubes while 65 17 indicates the ashpit.

The operation of the boiler will be apparent as it will be seen that water circulated through the headers 1 and 2 and their connecting tubes 3 will be quickly heated 70 by the hot gases from the furnace which pass not only upward all around the outside of the tubes 3 and the headers but are deflected downward to pass through the lower rows of small tubes 9 and then out through 75 the upper rows, a large heating surface and double return action being thus obtained so that quick heating with great economy is secured.

What I claim as my invention is: 80

In a boiler, a setting forming an inclosure having a furnace, an outlet in its rear wall, and a smoke box casing on its front wall; a plurality of superposed connected front water chambers disposed adjacent said casing and inclosed thereby, a plurality of tubes extending rearwardly from the uppermost chambers in parallel rows and provided on their rear ends with water chambers similar to the front ones, the latter chambers extending into said outlet and the lowermost one being supported on the said rear wall, a plurality of shorter tubes extending rearwardly from the lowermost front water chambers provided on their rear ends with 85 similar chambers spaced from the rear wall of the setting, the lowermost one of which rests on the furnace bridge, and smaller tubes extending through the aforesaid tubes and chambers the interiors of the lower ones of which communicate with the inclosure and the smoke box and of the upper ones with the smoke box and the said outlet. 95

Dated at Victoria this 19th day of May, 1919.

ROBERT JOSEPH NOTT.
